(57) **CLAIM**

The ornamental design for rake tines, as shown and described.

DESCRIPTION

FIG. 1 is a perspective view of the rake tines according to the present design;

FIG. 2 is a first, left end view of the rake tines illustrated in FIG. 1 showing the rake tines according to the present design;

FIG. 3 is a second, right end view of the rake tines illustrated in FIG. 1 showing the rake tines according to the present design;

FIG. 4 is a front side view of the rake tines illustrated in FIG. 1 showing the rake tines according to the present design;

FIG. 5 is a back side view of the rake tines illustrated in FIG. 1 showing the rake tines according to the present design;

FIG. 6 is a top view of the rake tines illustrated in FIG. 1 showing the rake tines according to the present design;

FIG. 7 is a bottom view of the rake tines illustrated in FIG. 1 showing the rake tines according to the present design; and,

FIG. 8 is a close-up, perspective view of the back side of the rake tines illustrated in FIG. 1.

The claimed design comprises the elements shown in solid lines. The broken lines represent portions of the rake and form no part of the claimed design.

The rake tines are shown with a symbolic break in its width. The appearance of any portion of the article between the break lines forms no part of the claimed design.
